FENCE POST

Walter R. Tetzlaff, Kalamazoo, Mich.

Application January 15, 1945, Serial No. 572,764

4 Claims. (Cl. 189—29)

1

This invention relates to improvements in fence posts.

The main objects of this invention are:

First, to provide a metal fence post to which the strands or wires of a fence may be quickly and at the same time securely attached, the wires being clutchingly engaged to prevent longitudinal movement thereof.

Second, to provide a post having these advantages with a ground engaging anchoring plate enabling the use of a post of relatively small cross section and at the same time provide one having substantial resistance to lateral pressure or thrust.

Objects pertaining to details and economies of the invention will definitely appear from the description to follow. The invention is defined in the claims.

A structure which embodies the features of the invention is clearly illustrated in the accompanying drawing, in which:

Fig. 1 is a fragmentary perspective elevation view of a fence post having the strands of a fence engaged therewith and shown in operative relation to the ground.

Fig. 2 is an enlarged horizontal section on line 2—2 of Fig. 1.

Fig. 3 is an enlarged fragmentary rear perspective view.

Fig. 4 is an enlarged horizontal section on line 4—4 of Fig. 1.

In the embodiment of my invention illustrated the post 1 is formed of angle steel of suitable dimension and has a plurality of longitudinally spaced transverse slots 2 in the angle of the apex thereof, each slot being spaced from the other slots to receive the longitudinal strands 3 of a fence, or the longitudinal strands may constitute a fence. I have shown plain wire strands in the accompanying drawing but the structure is adapted to receive multiple strand barbed wire.

The slots 2 are of such depth as to provide a space 4 between the strand and the inner angle of the post so that a headed fastener 5, suitably a nail, may be inserted in the space 4 and driven downwardly, the head not only providing a good impact surface to receive the blows of a hammer but also supporting the nail at an angle so that when it is driven down it engages the wire with a wedging action, forcing the wire into clutching engagement with the edges 6 at the ends of the slot and kinking or bending the wire as shown at 7. This results in securely clamping the wire with a clutching engagement so that it cannot slip longitudinally relative to the post.

2

The anchor plate 8 is formed of a flat rectangular piece of metal having a V-shaped offset 9 therein of such dimensions as to closely embrace the post, the anchoring plate being secured to the post by spot welding at 10. This provides oppositely disposed wings and the anchoring plate serves to reinforce the post at the point where it is most likely to bend or break, and constitutes an effective reinforcing element at this point. This condition results even though the anchor plate be of relatively thin material, and it also permits the use of relatively light material for the post. The anchor plate shaped and secured to the post as above set forth facilitates the stamping of the same from sheet or plate metal and also facilitates the nesting of the posts with anchor plates secured thereto into a relatively small space for shipping purposes.

It is a matter of experience that metal fence posts, even when of quite heavy material and of various cross sections, are likely to be bent at the surface of the ground by animals pressing against the fence. The anchoring plate of this invention serves the important functions of reinforcing the post at this point and providing more effective ground engagement at the point where greatest stress is applied to the post.

I have not attempted to illustrate or describe other embodiments or adaptations of the invention as it is believed this disclosure will enable those skilled in the art to embody the invention as may be desired.

Having thus described my invention what I claim as new and desire to secure by Letters Patent is:

1. A metal fence post of V-shaped cross section having a plurality of longitudinally spaced transverse slots in the angle thereof adapted to individually receive strands of wire, and an anchor plate having a central portion of V-shaped cross section, the sides of said V-shaped central portion being disposed in nesting engagement with and parallel to the sides of the post and spot welded thereto, said anchor plate projecting outwardly in opposite directions from the outer edges of the sides of its central V-shaped portion to provide anchoring wings, said wings being disposed substantially in a common plane to permit of the wings being disposed substantially parallel to the plane of a fence, said anchor plate being positioned to extend partially above and partially below the surface of the ground when the post is seated, there being a slot transversely across the apex of the anchor plate registering with the bottom slot of said post.

2. A metal fence post of V-shaped cross section having a plurality of longitudinally spaced transverse slots in the angle thereof adapted to individually receive strands of wire, and an anchor plate having a central portion of V-shaped cross section, the sides of said V-shaped central portion being disposed in nesting engagement with and parallel to the sides of the post and spot welded thereto, said anchor plate projecting outwardly in opposite directions from the outer edges of the sides of its central V-shaped portion to provide anchoring wings, said wings being disposed substantially in a common plane to permit of the wings being disposed substantially parallel to the plane of a fence, said anchor plate being of a generally rectangular outline with two of the diagonally opposed corner portions thereof disposed in vertical alinement with each other and in nesting engagement with the apex of the V-shaped post, said anchor plate being positioned relative to the post for one of said diagonally disposed corner portions being below the ground and for the other diagonally disposed corner portion being above the ground, the diagonally disposed corner portion above the ground having a slot extending transversely across the apex thereof and registering with the bottom slot of the post.

3. A metal fence post of V-shaped cross section having a plurality of longitudinally spaced transverse slots in the angle thereof adapted to individually receive strands of wire, and an anchor plate having a central portion of V-shaped cross section, the sides of said V-shaped central portion being disposed in nesting engagement with and parallel to the sides of the post and spot welded thereto, said anchor plate projecting outwardly in opposite directions from the outer edges of the sides of its central V-shaped portion to provide anchoring wings, said wings being disposed substantially in a common plane

to permit of the wings being disposed substantially parallel to the plane of a fence, said anchoring plate being positioned to extend partially above and partially below the surface of the ground when the post is seated and constituting a reinforcing member, there being a slot transversely across the apex of the anchor plate registering with the bottom slot of said post.

4. A metal fence post of V-shaped cross section having spaced means at the angle thereof to facilitate securing strands of spaced wires transversely of the post, and an anchor plate having a central vertical portion of V-shaped cross section, the sides of the central V-shaped portion being disposed in nesting engagement with and parallel to the sides of the post, and secured thereto, said anchor plate projecting outwardly in opposite directions from the outer edges of the sides of its central V-shaped portion and outwardly beyond the side edges of the post to provide anchoring wings, said anchor plate being of a generally rectangular outline with two of the diagonally opposed corner portions thereof disposed in vertical alinement and in nesting engagement with the apex of the V-shaped post.
